[57] CLAIM

The ornamental design for a cleaning head for an upright vacuum cleaner, as shown and described.

DESCRIPTION

FIG. 1 is a perspective view of a cleaning head for an upright vacuum cleaner, showing my new design;
FIG. 2 is a front elevational view thereof;
FIG. 3 is a top plan view thereof;
FIG. 4 is a left side elevational view thereof;
FIG. 5 is a right side elevational view thereof;
FIG. 6 is a rear elevational view thereof; and,
FIG. 7 is a bottom view thereof.

The broken lines in FIG. 1 are shown for illustrative purposes only and form no part of the claimed design.
